UNITED STATES PATENT OFFICE

1,969,315

RADIATOR

Anton R. Moller, Lexington, Mass.

Application February 8, 1933, Serial No. 655,713

4 Claims. (Cl. 257—159)

My invention relates to improvements in radiators for heating systems and the like and it has for its primary object to improve the construction and operation thereof.

5 A heating system or the like of the class in which my invention is used comprises a plurality of radiators, or equivalent devices, each of which is provided with an inlet connected by a supply conduit with the outlet of a heater or 10 the like, and also with an outlet connected by a return conduit with the inlet of the heater or the like.

A fluid heat-conveying agent such as water or 15 steam is circulated through the system either by gravity or by pressure and an objectionable feature characterizing such systems, as commonly constructed, has been that when the system included a plurality of radiators located at different distances from the heater, said radiators, or some of them, would not each receive 20 its proportionate supply of said agent.

In the case of a steam heating system where the heating agent was circulated by pressure each radiator of the system would be supplied 25 with steam at a rate that was inversely proportional to its distance from the heater. That is, the radiator nearest the heater would be served with more steam than the radiator that was farthest from the heater. This was due 30 to the fall in pressure and velocity of the steam as it progressed through the supply pipes leading from the heater, and to friction within said supply pipes.

In the case of a hot water gravity system the 35 radiators would each be supplied with the heat-conveying agent at a rate that was in direct proportion to the distance thereof from the heater. This was particularly the case where the radiators were disposed at different eleva- 40 tions.

Of course it is common practice to provide a 45 shut-off valve in each supply conduit closely adjacent to its radiator but such valves are continually being manipulated, each independ- 50 ently of the others, so that there never exists a predetermined and fixed relationship between the respective effective capacities of the several supply conduits of the system with the result that the rate of delivery to the different radiators can never be the same or approximately so, 55 particularly when operating at full capacity.

My invention has for one of its objects to ob- 60 viate this objectionable characteristic and one of its features consists in providing adjustable throttling means in the inlet conduit of each radiator, said throttling means being set and fixed in an adjusted condition which gives to said inlet conduit a definite permanent maxi- 65 mum capacity that is inversely proportional to

the pressure under which the fluid heat conveying agent is delivered to said radiator.

It is an advantage to my invention that the adjustable throttling means in the inlet conduit of each radiator can be set and permanently 65 fixed in its adjusted condition either before or after the radiator is incorporated in the system so as to give to said inlet conduit a maximum capacity which is either directly or inversely proportional to, and determined by, the distance 70 of its radiator from the heater, and so that when all of the radiators are operating at full capacity the heat-transmitting agent is equally distributed to the several radiators, or approxi- 75 mately so.

Other features and advantages of my invention are hereinafter pointed out.

In the accompanying drawings:

Figure 1 is a diagrammatic view illustrating a steam heating system provided with radiators 80 constructed in accordance with my invention.

Figure 2 is a sectional detail of a portion of one of the radiators shown in Figure 1.

Figure 3 is an elevation of a portion of one end of the radiator showing the inlet of the 85 latter.

Figure 4 is an end view of the nipple herein- 90 after described.

The steam heating system illustrated in Fig. 1 comprises three radiators 10a, 10b and 10c, 90 each of which is provided with an inlet port 11, Fig. 2, connected by a branch supply conduit 12 and riser 13 with the outlet 14 of a boiler 15. The outlets of the radiators are connected by branch conduits 16 and a common return conduit 17 with the inlet 18 of the boiler 15. In 95 each branch supply conduit 12 is provided the usual shut-off valve 19.

Each radiator also includes as a part thereof a nipple 20 having one end thereof disposed 100 within a chamber 21 formed in the end section of the radiator at the outer end of the inlet port 11 thereof as shown in Fig. 2. Chamber 21 is formed at its inner end with a conical seat 22 while the inner end of the nipple 20 is formed 105 exteriorly as a complementary cone frustum 23 which is tightly clamped against said seat by a sleeve nut 24 loosely mounted on nipple 20 and arranged with its inner end in abutting engagement with an annular radial flange or 110 shoulder 25 provided on nipple 20. The side wall of chamber 21 is threaded as at 29 to engage the exteriorly threaded nut 24.

The nipple 20 is tubular and it is interiorly threaded at its outer end to receive one end of 115 an ordinary pipe nipple 27 by which it is connected with the outlet port of the shut-off valve 19 of its radiator. At its inner end nipple 20 is made with an outlet port 26 that is eccentrically disposed with respect to the axis of said 120

nipple, while the inlet port 11 of the end radiator section is also eccentrically disposed with respect to the axis of nipple 20.

In order to insure proper engagement of the 5 conical portion 23 of the inner end of nipple 20 with the conical seat 22 on the radiator section, the contacting portion of said conical inner end of the nipple is made less in length than the depth of the conical portion of the 10 chamber 21 with the result that the flat inner end of the nipple is spaced away from the bottom of chamber 21 so as to provide a clearance 15 passage 28, as shown in Fig. 2, which is never closed.

15 Since the ports 26 and 11 are both eccentrically disposed with respect to the axis of nipple 20 it will be clear that by rotatively adjusting said nipple while the nut 24 is loose, the capacity of the inlet of the radiator can be varied 20 between a predetermined minimum and a predetermined maximum, which permits of fixing said capacity so that it accords with the delivery pressure at said radiator. After the nipple has been permanently set to accord with 25 said delivery pressure the nut 24 is set up tight thus making the joint between the conical inner end of the nipple and its seat steam tight and leakproof.

Since the radiators of the system are disposed at different distances from the boiler or heater 15 the delivery pressure at each will be different from that at the others, but by properly setting the nipples 20 of the system a uniform rate of delivery may be established 35 throughout the latter.

In order to facilitate the setting of the nipples 20 of the system the outer end portion of the nipple that is exposed to view may be marked with an index, or with a circumferential 40 series of indices, to co-operate with a fixed index mark provided upon a proximate portion of the exterior of the radiator section.

It is a feature of the above described construction that when the nut 24 is set up tight the 45 inner end surface of nipple 20 which surrounds the port 26 is held out of abutting engagement with the bottom of the conical inner end portion of the chamber 21 so that the ports 11 and 26 are always in communication, and in practice I 50 so construct the parts that when the nipple is set for minimum capacity the latter is about five percent of the maximum.

It is also a feature of the invention in its best 55 form that a single port 11 and a single complementary port 26 are provided since said ports may then be made semi-circular, as viewed endwise, thereby securing a greater range of capacity variation than would be possible with a plurality of ports 11 and a plurality of ports 26.

60 Also, a single pair of ports 11 and 26 is advantageous and desirable in order to provide for coarse and therefore accurate throttling adjustment of the nipple 20 since the greater the number of pairs of ports the more minute or finer 65 will be the adjustment for a given variation. The construction illustrated provides for an adjustment of the nipple 20 one hundred and eighty degrees to vary the capacity from maximum to minimum.

70 It is a feature of advantage to the above described construction that the shut-off valve 19 is disposed in the branch conduit 12 between

the nipple 20 and the source of supply, and the position or condition of said valve 19 is not disturbed while making adjustment of said nipple. Therefore, while making such adjustment the valve 19 may remain closed so that escape 80 of the heat-conveying fluid is impossible while the nipple is being adjusted.

What I claim is:

1. A radiator of the character described having an inlet provided with an adjustable throttler 85 union of variable capacity whereof one end part is integral with said radiator and comprising an opposite end part consisting of a nipple unit having endwise abutting engagement with said radiator and rotatively adjustable relatively to the latter thereby to vary the capacity of said union between a predetermined minimum limit and a predetermined maximum limit, each of said end parts being made with an eccentrically disposed port co-operatively associated with the eccentrically disposed port of the other part, and means for fixing said nipple in its adjusted 90 position consisting of a threaded sleeve surrounding said nipple unit and abutting an annular radial shoulder provided upon the latter, the said sleeve having threaded engagement with said radiator.

2. A radiator constructed in accordance with claim 1, wherein the said nipple and radiator are made with complementary abutting conical surfaces which are held in contact by said threaded sleeve.

3. A radiator of the character described having an inlet formed adjacent to its outer end with a relatively large circular threaded chamber and 110 at its inner end with a relatively small eccentrically disposed outlet port; a rotatively adjustable nipple unit extending into said chamber and formed adjacent to its inner end with a conical surface to seat against the bottom of said 115 chamber and also with an annular shoulder, said nipple unit having its outer end portion constructed for attachment to one end of a conduit and being constructed at its inner end with an eccentrically disposed outlet port co-operatively 120 associated with the eccentrically disposed outlet port of said inlet, and an exteriorly threaded sleeve nut screwed into said chamber and engaging said annular shoulder to hold said conical surface seated against the bottom of said chamber 125 and to fix said nipple unit in its adjusted position.

4. A radiator of the character described having an inlet port provided with an adjustable throttler union of variable capacity whereof one 130 end part is integral with said radiator and comprising an opposite end part consisting of a nipple unit having endwise abutting engagement with said radiator and rotatively adjustable relatively to the latter thereby to vary the capacity 135 of said union between a predetermined minimum limit and a predetermined maximum limit, each of said end parts being made with an eccentrically disposed port co-operatively associated with the eccentrically disposed port of the other 140 part, and means for fixing said nipple in its adjusted position consisting of a sleeve loosely surrounding said nipple unit and abutting a radial shoulder provided upon the latter, and means to force and hold said sleeve against said 145 shoulder,

ANTON R. MOLLER.
